WINDOW SASH CATCH

Arthur Ringzelli, Chicago, Ill.

Application September 29, 1953, Serial No. 27,007

Term of patent 7 years

(Cl. D10—10)

FIG. 1.

FIG. 2.

FIG. 3.

Figure 1 is a front perspective view of a window sash catch in operative position, showing my new design;

Figure 2 is a rear view; and

Figure 3 is a sectional view taken on the line 3—3 of Fig. 2.

I claim:

The ornamental design for a window sash catch, as shown.
